UNITED STATES PATENT OFFICE.

GENE HERZ, OF CHICAGO, ILLINOIS, ASSIGNOR TO HERZ BED COMPANY, OF CHICAGO, ILLINOIS, A CORPORATION OF ILLINOIS.

DAY BED AND THE LIKE.

Application filed May 31, 1923. Serial No. 642,876.

My invention relates to day beds and the like and more particularly to the type in which the movable or extension bed section is connected to the stationary or main bed section so as to be supported in superimposed position over the latter when the bed is in closed condition.

The principal object of my invention is to provide a simple and compact bed of this type which may be used as a couch or seat when closed, or as a double-bed when opened or extended, and which employs a spring mattress structure for each bed section formed of suitably spaced spiral bed springs, which are far more comfortable and satisfactory than the meshed wire fabric ordinarily used in day beds to support, as do the bed springs in my construction, the fiber or hair mattress cushions or pads. More specifically, I have applied my invention to the form of day bed in which the movable or extension bed section is pivoted to the stationary or main bed section by links, so that the movable bed section is supported in superimposed position over the main bed section when the bed is closed, and may be swung with its mattress in a substantially horizontal plane when the bed is extended, and for the purpose of accomplishing the principal object of my invention, I have supported the coiled spring mattress structure of the main bed section so that it is elevated thereon automatically while the bed is being extended and is lowered automatically while the bed is being closed. If the bed spring structure of this coiled spring type was maintained in a fixed or immovable position on the main bed section, the extension bed section would have to be supported inordinately and uncomfortably high when the bed is in closed condition, in order to accommodate the coiled bed springs of the main section, and to provide the proper clearance between the rear edge of the extension bed section and the front springs of the main bed section while the extension bed section is being swung to or from its superimposed position over the main bed section. Further objects of the invention, among others, are to provide simple, compact and efficient means for raising and lowering the coiled spring mattress section of the main bed section and maintaining it in elevated position when

the bed is extended; to employ an improved spring and link arrangement to assist the user in operating the bed, the arrangement being such that the springs retard or cushion the final extents of movement of the extension bed section to its full extended and closed positions and assist in the initial movements of the same from either of such positions; and to form the links connecting the extension and main bed sections together so as to permit ornamental detachable bed ends to be secured to the front legs of the main bed section by fastening devices like those securing the detachable bed ends to the rear legs of the main bed section, hence permitting a detachable bed end to be applied to either end of the bed, the bed ends being interchangeable.

With the above and incidental objects in view the invention consists in certain novel features of construction and combination of parts, the essential elements whereof are recited in the appended claims and a preferred form of embodiment of which is described in detail hereinafter and illustrated in full in the accompanying drawings which form part of this specification.

Of said drawings, Fig. 1 is a plan view of one of the end portions of a bed embodying my invention, the bed being shown in extended condition with the hair or fiber mattress cushions or pads removed; Fig. 2 is an end elevation of the bed in extended condition; Fig. 3 is a view similar to Fig. 2, but shows the bed in closed condition; Fig. 4 is a detail sectional view through one end of the main or stationary bed section being taken substantially on the line 4-4 of Fig. 2; Fig. 5 is a detail sectional view taken through the end of both the main and extension bed sections and showing the latter in superimposed position over the former, the section being taken substantially on the line 5-5 of Fig. 3; Fig. 6 is a top plan view of one end portion of the main bed section with the spiral bed springs removed and the detachable bed end shown in section as on the line 6-6 of Fig. 7; Fig. 7 is an end view of the bed in closed condition and provided with a detachable bed end; Fig. 8 is a detail front view of one end portion of the bed, showing the bed in closed condition with the detachable bed end attached; Fig. 9 is an end view of a bed of a modified form,

2 showing the spring mattress structure of extension bed section in spaced relation from the spring mattress structure of the main bed section when the bed is in closed condition; Fig. 10 is an end view showing the bed of Fig. 9 in extended condition; Fig. 11 is a detail sectional view through one end of the main bed section, being taken substantially on the line 11—11 of Fig. 9 and 10 showing the extension bed section in superimposed position; and Fig. 12 is a detail sectional view through the main bed section as on the line 12—12 of Fig. 10.

Referring to the drawings showing the 15 preferred form of embodiment of my invention, the extension bed section comprises an end frame at each end connected by side bars, each end frame consisting of a front leg 15 and a rear leg 16, both formed of 20 angle iron, a flat bar 17 connecting the upper ends of the legs and a flat bar 18, which is under and parallel to the bar 17 and likewise connected at its ends to the legs 15 and 16. Connecting side bars 19, one on the 25 front and the other at the rear of the main bed section, are riveted at their ends to the legs. Mounted on the main bed section, in the manner to be presently described, is the spring mattress structure preferably comprising 30 the spiral coiled bed springs 21 which are suitably connected together at their upper ends in any approved way and which support the border wire or rod 22. The springs at their lower ends are mounted 35 on the transverse bars or slats 23 secured at their end to longitudinal side bars 24, formed of angle iron, and connected together near their ends by cross bars 25, also formed of angle iron.

40 The movable or extension bed section comprises end cross bars 26 connected together by front and rear side bars 27 and 29, respectively, and preferably formed integral with legs 28 at their forward ends, these 45 bars and legs being preferably formed of angle iron. An angle bar 30 is connected at its ends to the legs 15 intermediate their ends. The spring mattress structure of the extension bed section is preferably like that 50 of the main bed section except that the slats 23' of the former are connected at their ends to the side bars 27 and 29 connected to the end frames, while the slats 23 of the latter are connected to the supporting bars 24 55 which are not fastened directly to the end frames of the main bed section, as will be more fully explained presently. The coiled bed springs of the mattress structure of the extension bed section are numbered 21'.

60 The extension bed section is swingingly supported upon the main bed section by pairs of parallel links 31 and 32, it being understood that each end of the bed is provided with a pair of these links. The upper 65 ends of the links are connected to the end bars 26 by studs 33 while the lower ends of the links 31 are connected to the lower cross-bars 18 by means of studs 34. As best shown in Fig. 4, the lower ends of the links 32 are secured to long studs 36 which extend 70 into the hollow ends of a longitudinal rod or rock shaft 37 and are secured thereto in any desired manner. The rock shaft 37 is supported in bearings 38 secured to the underside of cross-bars 39 connected at their 75 ends to the side bars 19. The studs 36 project through openings in the end bars 18 and the links 32 are suitably spaced from the bars 18 by means of spacing collars 39'.

It will be evident that, when the bed is in closed condition, as shown in Fig. 3, the lower edges of the vertical flanges of the end bars 26 and rear side bar 29 of the extension bed section rest on top of the end bars 17 of the stationary section, the movable section being firmly supported in this manner in superimposed position on the stationary bed section. When the bed is to be extended the forward side bar 27 of the extension section is grasped and this section is pulled forwardly, the links 31 and 32 serving to guide and support the extension bed during such movement. When the bed is in its full extended condition, the front side of extension bed section is supported by its legs 28 on the floor and the rear ends of the end bars 26 rest on top of the forward legs 15 of the main bed section, as best shown in Fig. 2.

As will be seen by observing Fig. 3, the spring mattress structure of the main frame section is in its lowered position when the bed is closed, the top surface of the structure then being below the top edges of the end bars 17, and by observing Fig. 2 it will be seen that this mattress section is in elevated condition, when the bed is in open or extended condition, so that the spring mattress structures of the two bed sections are in the same horizontal plane to act, in effect, as a double-bed or adjacent twin-beds. The means for raising and lowering the spring mattress structure of the main bed section, when the bed is operated, will now be described.

At each end of the bed a pair of toggles are pivoted to the vertical flanges of the cross bars 25 and 39, each toggle comprising a pair of links 40 and 41, with the link 41 pivoted at its lower end to the cross bar 39 and the link 40 pivoted at its upper end to the cross-bar 25 and the two links pivoted together at their overlapping ends by a stud 42. The studs 42 of the toggles at each end of the bed project through the ends of a connecting bar or link 43. Fast to the rock shaft 37 and adjacent each cross-rod 39 is an operating arm 44 provided with a laterally extending stud 45 which projects under the corresponding cross-bar

43. The link 41 of each of the forward toggles is provided with an upward extension 47 having its outer end inclined slightly.

5 From this description it will be seen that, when the extension bed section is swung from the closed position shown in Fig. 3 to the extended position shown in Fig. 2; the rock-shaft 37 and arms 44 are rocked counter-clockwise, the links 32 being fast to the rock-shaft 37, and during this movement the studs 45 engage the lower edges of the cross-bars 43 of the toggle equipment thereby raising these cross-bars to the 15 position shown in Fig. 2. During this elevation of the cross bars the toggles are extended, thereby raising the spring mattress structure of the main bed section to its elevated position in which it is in horizontal alignment with the spring mattress structure of the extension bed section. When the bed is in its full extended condition, the studs 45 are in substantially vertical alignment above the cross-shaft 37 and at the 20 same time the outer ends of the extensions 47 of the forward links 41 engage under the horizontal flanges of the cross-bars 25 of the supporting frame of the spring mattress structures, so that the studs and extensions firmly maintain the spring mattress structure in its elevated condition while the bed is full extended, the weight of the movable bed section, together with its mattress cushions or pads and bed 25 clothes, serving to maintain the supporting condition of the studs 45 and extensions 47. The spring mattress structure of the main bed section is raised and lowered rectilinearly, that is straight up and down, 30 unaccompanied by any swinging lateral movement. It will be observed that, when the bed is in closed condition, the studs 45, as shown in Fig. 3, are considerably below the cross-bars 43 so that the extension bed section is partly raised by the initial swinging of the links 31 and 32 before the elevation of the spring mattress structure of the main bed section begins and that the rear side bar 29 of the extension bed section is moved forwardly as the 35 spring mattress structure of the main bed section is being elevated so that this side bar 29 does not contact with the forward upper edge of this mattress structure, clearance being provided in this way. While the bed is being closed the reverse action takes place, the weight of the spring structure mattress of the main bed section being sufficient to lower the same as the 40 studs 45 are swung downward. The downward movement of the spring mattress section is limited by the engagement of the lower ends of the links 40 with the cross bars 39. When the bed is in closed condition, the cushions or pads on the extension

bed section are at the proper height from the floor to afford a suitable seat or couch, and when the bed is extended its mattress sections are at substantially the same height as the usual position of mattresses on ordinary beds.

I have provided suitable means for assisting the user in opening and closing the bed such means including springs 48 and 49, there being a pair of these springs at 45 each end of the bed. The outer ends of the springs of each pair are connected to the free ends of corresponding arms 50 pivoted to the end bars 17 of the main bed section, while the inner ends of the springs of each pair are connected to the ends of arms 51 pivoted on a stud projecting from a bracket 52 which is riveted on the link 32. While the bed is being closed, it will be apparent that the springs 49, being tensioned when the bed is in extended condition, assist the operator in moving the extension bed section from its position of rest on the floor—that is during the initial movement of this section—until the links 32 are substantially in a vertical position, and that after they pass this position the forward springs 48 become tensioned and aid in preventing too-rapid movement of the extension bed section to its final position of rest on the main bed section, the arms 50 and 51 being rocked to accommodate the movements of the springs. When the extension bed section is moved from its closed to its open position the reverse action of the springs and arms takes place.

In Figs. 6, 7 and 8, I have shown an application of detachable ornamental bed ends 55 to my improved bed, a bed end being employed at each end of the bed. The lower ends of the legs of the bed ends are provided with laterally extending supporting devices 56 provided with vertical pins 57 which are adapted to project through suitable openings in the horizontal portions of angle plates 58, riveted to the lower ends of the legs 15 and 16 of the main bed section. Links 59 are pivoted to the sides of the bed ends and they are provided with notches which are adapted to engage over headed pins 60 projecting from the sides of the legs 15 and 16. It is obvious that the bed ends may be readily applied to or detached from the bed and that a customer may purchase the bed alone or with the bed ends, at his option. It will be seen that the links 31 are bent so that, when the bed is in extended condition, they extend over the forward hooks 59 connected to the legs 15 so that there is no interference between the links and the hooks. Heretofore in this type of bed with the swinging connecting links, it was customary to connect the rear ends of the bed ends to the rear legs of the stationary section and the front ends of the bed ends to

one of the end cross-bars to accommodate movement of the forward links connecting the main and extension bed sections, thus providing two forms or dissimilar places of connections which prevented the foot and head bed ends from being interchangeable. With my improved construction like connections are employed on each side of the bed ends, thus facilitating the connection and 10 disconnection of the bed ends to the bed and permitting their interchangeability.

Referring now to the modified form shown in Figs. 9 to 12, it will be seen that this modified form in most respects is substantially the same as the construction of the preferred form, and therefore I have used like reference numerals to designate corresponding parts. The links 31 and 32 of the modified form are substantially parallel and somewhat longer than the corresponding links of the preferred form, so that when the bed is in closed condition, the spring mattress structure of the extension bed section is in spaced relation from 20 the spring mattress structure of the main bed section, the front side bar 30 then being in engagement with the forward sides of the legs 15 and the extension section being supported by the links 31 and 32. This space 25 between the two sections provides an admirable storage place for the bed-clothes when the bed is closed. As I have not shown bed ends connected to this preferred form of bed I have shown the links 31 as being 30 formed of straight bars instead of bent bars as in the preferred form. In my modified form, the links 41 of the toggles are pivoted directly on the lower cross-bars 18 and the upper ends of the links 40 are pivoted 35 directly to the cross-bars 25, which are secured to the very ends of the longitudinal bars 24 of the spring mattress supporting frame. The rock shaft 37 is journaled at its ends in and supported by the lower cross-bars 18. The cross-bars 43, connecting the 40 toggles, are pivotally connected to the links 41 above the pivotal connections of the latter with the links 40. The lower edges of the bars 43 are provided with notches which are 45 engaged by the studs 45 during movement of the bars by the studs 45.

The adjacent ends of the springs 48 and 49 in my modified form are secured to the arms 51 pivoted on the arms 44, instead of 50 on the links 32 as in the preferred form. The opposite ends of these springs are connected directly to the side bars 19. An arm 60 is secured to the center of the rock shaft 37 and at its free end is connected to one 60 end of a spring 61 while its other end is connected to the front side bar 19. The springs 48, 49 and 61 cooperate in an obvious manner to assist the operator in opening and closing the bed. When the bed is in closed 65 condition, the forward arms 51 near their

outer ends engage the rock shaft 37 and hence the springs 48 are extended, while at the same time the springs 49 and 61 are also extended due to the positions of the arms 44 and 61. It is also clear that when the bed is 70 in opened condition all of the springs are extended more or less and hence co-act in cushioning or retarding movement of the extension bed section to its full extended condition. 75

The legs 15 of the main bed section are provided with brackets or projections 62 which are engaged by and support the rear ends of the end bars 26 of the extension bed section when the bed is in extended condition. The operation of the modified bed is substantially the same as that of the preferred form, explained above. 80

It will be understood that the invention is susceptible of various changes and modifications all coming within the scope and spirit of my invention as defined in the following claims. 85

I claim:

1. In a bed, the combination of a main 90 bed section, an extension bed section, means connecting said sections to permit movement of said extension bed section in an upright condition to extended and closed positions, spring mattress structures for 95 said bed sections, toggles connecting the main bed section and its spring mattress structure, and mechanism operated by said connecting means for extending said toggles to raise the spring mattress structure of the main bed section when moved to opened or extended condition. 100

2. In a bed, the combination of a main bed section, an extension bed section, a rock 105 shaft on said main bed section, links connected to said extension bed section and said shaft, a spring mattress structure comprising coiled bed springs for each bed section, toggles connecting said main bed section and its spring mattress structure, means connecting said toggles, and arms on 110 said shaft for engaging said connecting means to extend the toggles and hence raise the spring mattress structure of the main bed section when the extension bed section 115 is moved to extended position.

3. In a bed, the combination of a main bed section, an extension bed section, a rock shaft on said main bed section, links connected to said shaft and said extension bed 120 section, a spring mattress structure on each bed section, pairs of toggles at each end connecting the main bed section and its spring mattress structure, bars connecting the toggles at each end, and means on said 125 shaft for raising said bars to extend the toggles and raise the spring mattress structure of the main bed section when the extension bed section is moved to extended position. 130

4. In a bed, the combination of a main bed section, a spring mattress structure therefor, an extension bed section, a spring mattress structure therefor, means connecting said sections to permit said extension section to be moved in upright condition to extended or closed position, and means including toggles connecting the main bed section and its spring mattress structure and a lost-motion connection for automatically raising the spring mattress structure of the main bed section while the bed is being opened and after the extension bed section has been partially operated.
5. In a bed, the combination of a main bed section, an extension bed section, links connecting said bed sections to permit the extension bed section to be moved to extended and closed positions, arms operated by said links, a spring mattress structure, comprising coiled bed springs, for said main bed section, a spring mattress structure for the extension bed section, and toggles connected to the main bed section and its spring mattress section, supporting the spring mattress structure of the main bed section on such section and operated by said arms to raise said spring mattress structure after the extension bed section has been partially operated.
6. In a bed, the combination of a main bed section, an extension bed section, a rock shaft on said main bed section, links connected to said shaft and said extension bed section, a spring mattress structure on each bed section, pairs of toggles at each end connecting said main bed section and its spring mattress structure, bars connecting the toggles at each end, arms on said shaft carrying pins underlying said bars and adapted to engage said bars after the extension bed section has been partially operated to raise the spring mattress structure of the main bed section.
7. In a bed, the combination of a main bed section, an extension bed section, means connecting said sections to permit movement of said extension bed section in an upright condition to extended and closed positions, a spring mattress structure for each bed section, toggles connecting the main bed section to its spring mattress structure, mechanism operated by said connecting means for extending said toggles to raise the spring mattress structure of the main bed section when the extension bed section is moved to open or extended position, and means associated with said toggles to aid in maintaining the bed in opened condition.
8. In a bed, the combination of a main bed section, an extension bed section, means connecting said sections to permit movement of said extension bed section to its extended or closed position, a spring mattress structure for each bed section, toggles connecting the main bed section and its spring mattress structure, mechanism operating by said connecting means for extending said toggles to raise the spring mattress structure of the main bed section, and extensions on arms of said toggles serving as supports for the spring mattress structure of the main bed section when the bed is open.
9. In a bed, the combination of a main bed section, an extension bed section, means connecting said sections together, a spring mattress structure for each bed section, and toggles connecting the main bed section and its spring mattress structure, each toggle comprising a pair of links pivoted to the main bed section and its spring mattress structure, respectively, one of the links being extended to form a direct connection between the main bed section and its spring mattress structure when the bed is in open condition.
10. In a bed, the combination of a main bed section, an extension bed section, a rock shaft on said main bed section, links connected to said shaft and said extension bed section, a spring mattress structure for each bed section, pairs of toggles at each end connecting the main bed section with its spring mattress structure, bars connecting the toggles at each end, and arms on said shaft for cooperating with said bars to raise the spring mattress structure of the main bed section, the arms being in a substantially vertical position when the bed is in extended condition.
11. In a bed, the combination of a main bed section, an extension bed section, means including links for connecting the bed sections together to permit the extension bed section to be moved to extended and closed positions, arms pivoted at the front and rear on said main bed section, arms pivoted on said means and projecting forwardly, arms pivoted on said means and projecting rearwardly, and front and rear springs connected at their opposite ends to the free ends of the respective front and rear arms on said main bed section and said means to assist the initial movement of the extension bed section from either position of rest and retard final movement of said extension bed section to either of said positions.
12. In a bed, the combination of a main bed section, an extension bed section, links at each end connecting said sections, and arranged to permit movement of said extension bed section in an upright condition to extended and closed positions, a spring mattress structure for each of said bed sections, collapsible arms spaced apart at each end of the bed and in direct engagement with said main bed section and its spring mattress structure, and mechanism operated by one of said connecting links for moving both said collapsible arms at each end of the bed to

raise the spring mattress structure of the main bed structure as the extension bed section is moved to its open position.

13. In a bed, the combination of a main bed section, an extension bed section, links at each end connecting said sections and arranged to permit movement of said extension bed section in an upright condition to extended and closed positions, a spring mattress structure for each of said bed sections, arms at each end of the bed connected together for simultaneous movement, said arms being in constant engagement with said main bed section and its spring mattress structure for raising said spring mattress structure and supporting it raised, and mechanism operated by one of said connecting links for moving said connected arms to raise the spring mattress structure of the main bed

structure as the extension bed section is moved to its open position.

14. In a bed, the combination of a main bed section, a spring mattress structure therefor, an extension bed section, a spring mattress structure therefor, links at each end of the bed connecting said sections and arranged to permit said extension section to be moved in an upright condition to extended or closed positions, and means including arms at each end of the bed directly connected to the main bed section and also to its spring mattress structure and lost-motion connections operated by certain of said links for automatically raising the spring mattress structure of the main bed section while the bed is being opened and after the extension bed section has been partially operated.

GENE HERZ.
